(57) **CLAIM**

The ornamental design for a toy hook, as shown and described.

DESCRIPTION

FIG. 1 is a perspective view of a first embodiment of a toy hook according to an embodiment of the disclosure;

FIG. 2 is a side view thereof;

FIG. 3 is a side view thereof;

FIG. 4 is a front view thereof;

FIG. 5 is a rear view thereof;

FIG. 6 is a top view thereof;

FIG. 7 is a bottom view thereof; and,

FIG. 8 is a perspective view of a second embodiment of a toy hook according to an embodiment of the disclosure. The second embodiment is identical to the first embodiment except for the inclusion of candy cane like strips.

The broken lines represent portions of the structure that forms no part of the claim.
